Patented Apr. 15, 1919.

THE NORRIS PETERS CO., PHOTO-LITHO., WASHINGTON, D. C.

UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

ORDNANCE SIGHTING APPARATUS.

1,300,353.

Specification of Letters Patent. Patented Apr. 15, 1919.

Application filed June 21, 1917. Serial No. 176,111.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Ordnance Sighting Apparatus, of which the following is a specification.

This invention relates to sighting apparatus of the cam elevated type and in which the elevating cam is situated at a substantial distance from the axis of elevation of the sight bracket. The invention is thus particularly applicable to sighting apparatus for use in connection with casemate gun mountings in which the range dial, arranged concentric with the elevating cam, is situated near the rear end of the casemate shield and the sight bracket is situated contiguous to the gun trunnions, the cam operating upon an extension or range arm rigid with the sight bracket. In such an arrangement the size of an elevating cam capable of giving the usual maximum range adjustment to the sight bracket is considerable; when therefore it is desired with this arrangement to impart large range adjustment (for example practically double the usual adjustment) the size of the elevating cam, when a single cam is employed, would become prohibitive; the chief object of the present invention is to avoid this difficulty.

According to the invention the cam instead of operating directly upon the range arm operates thereon through the intermediary of a longitudinally movable bar, or similar member which is pivotally or similarly connected to the range arm at a point whose distance from the axis of elevation of the sight bracket is as small as is practicable; in this manner it becomes possible to impart the aforesaid large range adjustments to the sight bracket by means of a cam no larger than that at present employed for imparting the usual range adjustments.

In order that the said invention may be clearly understood and readily carried into effect we will describe the same more fully

with reference to the accompanying drawings, in which:

Figure 1 is a side elevation and Fig. 2 a plan showing sighting apparatus constructed in accordance with our invention.

Fig. 3 is a horizontal section drawn on a larger scale taken approximately on the line *xx* of Fig. 1.

A is the sight bracket which is pivoted concentrically or approximately concentrically with the gun trunnions and A' is the sight carrier. A² is the range arm which is upwardly and rearwardly inclined and which is connected by a transverse frame or bar A³ to a similar range arm situated at the opposite side of the mounting. B is the elevating cam which operates upon the range arm A² through the intermediary of the bar C.

In the example shown the bar C is pivoted at *c* to the range arm A² of the sight bracket, the distance of the point *c* from the axis of elevation of the sight bracket being made as small as is practicable so as not to increase unnecessarily the size of the cam B. The rear end of the bar C is forked to receive a block c' which is capable of sliding in a guide or bracket B' attached to the gun cradle and supporting the cam B and the range dial B². The forked end of the bar C is connected to the block c' by means of a screw c² the ends of which are cylindrical to form a pivotal connection for the said forked end of the bar. This screw also carries a roller C' bearing against the cam B under the influence of a spring b which surrounds the forward part of a sliding rod b' connected with the said block c'. This part of the rod is contained within a casing b² having hollow nuts b³ b⁴ at its ends through which the rod extends and can slide. One end of the spring bears against the nut b³ and the other end against a collar b⁵ on the said rod, which collar bears against the nut b⁴ for restricting the rearward movement of the rod. When the cam B is actuated to increase the range setting of the sight the roller C' the block c' and the pivot screw c² move in a rectilinear path along the guide B' against the resistance of the spring b and at the same time transmit forward move-

ment to the bar C for operating the range arm A² the ends of the bar C turning about the pivot screw c² and the pivot c respectively.

5 What we claim and desire to secure by Letters Patent of the United States is:—

1. In ordnance sighting apparatus, the combination with the sight bracket, of a cam, a longitudinally movable member interposed between the cam and the sight bracket, means for guiding said member, and a common support for said elements.

10 2. In ordnance sighting apparatus, the combination with the sight bracket, of a cam, a longitudinally movable member operated upon by the cam and pivoted to the sight bracket, means for guiding said member, and a common support for said elements.

15 3. In ordnance sighting apparatus, the

combination with a gun cradle and the sight bracket pivoted to the gun cradle, of a cam mounted on the gun cradle, a longitudinally movable member operated upon by the cam and pivoted to the sight bracket, and means 25 carried by the gun cradle for guiding said member.

4. In ordnance sighting apparatus, the combination with a gun cradle and the sight bracket pivoted to the gun cradle, of an arm 30 on said bracket, a cam mounted on the gun cradle, a longitudinally movable bar operated upon by the cam and pivoted to said arm and means carried by the gun cradle for guiding said bar.

35 In testimony whereof we affix our signatures.

ARTHUR TREVOR DAWSON.
GEORGE THOMAS BUCKHAM.
